ATTORNEY

UNITED STATES PATENT OFFICE.

JAMES W. BRYCE, OF BINGHAMTON, NEW YORK, ASSIGNOR TO THE INTERNATIONAL TIME RECORDING COMPANY, OF NEW YORK, A CORPORATION OF NEW YORK.

CLOCK-SYNCHRONIZING DEVICE.

1,310,789.

Specification of Letters Patent.

Patented July 22, 1919.

Application filed May 8, 1919. Serial No. 295,593.

To all whom it may concern:

Be it known that I, JAMES W. BRYCE, a citizen of the United States, residing at Binghamton, in the county of Broome and 5 State of New York, have invented certain new and useful Improvements in Clock-Synchronizing Devices, of which the following is a full, clear, and exact description.

The following is a description of the system for synchronizing clocks which is now well known in the art and upon which the invention which forms the subject of this application for Letters Patent is an improvement. 10
A master clock is connected up in circuit with a plurality of secondary clocks, and to this circuit it connects a source of current for a specified time, usually fifteen minutes at some given time, as, for instance, once an 15 hour, from fifteen minutes of the hour to the even hour. Each secondary clock contains two electro-magnets in circuits which are connected by such clocks for specified intervals during each hour in definite relation 20 to the time as indicated by such clocks with the line circuit. One of said magnets controls means that permit the clock to run above normal speed, and the other, means for retarding its rate. The circuit closer 25 controlling the former magnet connects its circuit with the line for a given interval, say fifteen minutes, beginning at the even hour, as indicated by its hands, and the other for a like interval, beginning at approximately 30 thirty minutes of the hour, as also indicated by its hands. From this it results that if the clock be too slow the accelerating magnet will be energized before the end of the period of current flow maintained by the 35 master clock, or if too fast the retarding magnet will be energized after the beginning of such period of flow, with the result that the secondary clock will be either accelerated or retarded, as the case may be, 40 until it is brought into synchronism with the master clock.

In this system as I have heretofore constructed the apparatus, at least two controlling magnets were required in each secondary clock, and more or less complicated mechanism used for coöperating therewith, but I have now devised a plan of construction by means of which one magnet may be

dispensed with, and in which a very simple form of mechanism may be employed to accomplish the same result. 55

This improvement is illustrated in the accompanying drawings, in which—

Figure 1 is a diagrammatic illustration of the improvement as applied to a secondary clock, and 60

Fig. 2 is a sectional view of a differential gear forming part of the clock train.

The master clock, the line circuit and the means employed in connection therewith for connecting to line a current for given intervals at predetermined times are not illustrated herein as they are now well known, and it is sufficient for purposes of this case to state that the electro-magnet A in the secondary clock is by such means energized for exactly fifteen minutes each hour, the period of activity beginning at fifteen minutes of the hour and ending at the hour, true or master clock time. 75

The secondary clock, and it will be understood that there are as many such clocks in the circuit as may be required, and that they are all of the same construction, has any proper train of wheels B containing a differential gear C of the usual and known construction, with one main gear D of which engages the pinion of an ordinary escapement and balance E, and with the other main gear F of which engages the pinion of a rotary fan G, having fixed thereto a toothed wheel H, normally locked by a lever K so that the train as a whole runs under the control of the escapement and balance wheel E. 80 85 90

Fixed to the hour shaft of the secondary is a cam disk L, having a raised portion M of such extent as to require fifteen minutes in passing any given point. Upon the periphery of this cam bears a roller carried by 95 a lever N pivoted at O and normally held in contact with the cam by a spring P.

The lever N engages with a slot in a link or bar Q pivoted to one arm of lever K and having a hooked upper end adapted to be 100 shifted by the engagement of the roller on lever N with the raised portion of the cam L. The magnet A is provided with a pivoted armature R over which the hooked end of link Q is adapted to be shifted by the 105 lever N.

These parts are so arranged that the lever N is engaged by the high portion of the cam L for fifteen minutes each hour, beginning at thirty minutes and ending at fifteen minutes of the hour, according to the time as indicated by the secondary clock, hence if the clock be slow the lever N will not drop off the raised portion M at fifteen minutes of the hour, true time, but at some later instant, and hence the link Q will be shifted so as to bring its hooked end over the end of armature R, during a period of fifteen minutes which overlaps that during which the magnet A is due to be energized. That is to say, the armature will be raised, the link Q lifted and the fan released during such overlapping interval, from which it results that the secondary clock speeds up until it is brought to synchronism when the link Q is drawn out of engagement with the armature R.

As above stated, the raised portion M of the cam requires exactly fifteen minutes to pass a given point, and in conjunction with the cam is a second lever S with a point which engages and is raised by the high point at fifteen minutes of the hour according to the hands of the secondary and is dropped at the even hour. In other words, the lever S is raised by one end of M at the instant that lever N drops from the other.

The lever S engages with a link T pivoted to an arm X fixed to the armature R, by a pin working in a slot in the said link, and when the lever S is in engagement with the high point M the armature cannot be raised as the link T is locked by lever S.

If the clock is in exact synchronism with the master clock, the period during which the lever S is raised coincides exactly with that during which the magnet A is energized and nothing happens. But should the clock be too fast then the lever S will drop off M before the end of this period of energization with the result that the armature R is raised and the link T thrown to the left.

Connected with the link T by a link U is a spring actuated lever V carrying a light brake W which by this movement is brought into engagement with the periphery of the balance wheel, with the result that the escapement E and with it the clock train is stopped until the master clock catches up with it.

The operation by which the fan G is released, involves an upward movement of the armature R, which is at that time free to shift the link T and arrest the escapement E, but this is without sensible effect, as the clock train is free to run through that member of the differential which engages with the fan pinion. On the other hand, when the armature is raised to stop the clock it has no effect upon the fan, as at such times the link Q is not engaged by the armature.

It is manifest from the above that the objects of the synchronizing system which is set forth and broadly claimed in previous applications filed by me, notably in Serial No. 235,813, filed May 21, 1918, are accomplished by the means herein described, but by apparatus of a different character. So far as the broad principle, however, is concerned, this mechanism possesses the same advantages as the others which I have devised for the purpose.

What I now claim is—

1. A synchronizing mechanism for secondary clocks comprising in combination a clock train, means for retarding and means for accelerating its rate, an electro-magnet adapted to be energized for definite periods of predetermined extent by a master clock, an armature for said magnet and means operative for definite periods in fixed relation to the time as indicated by the secondary clock to cause said armature to operate the retarding or the accelerating means when the normal relations of such periods to the periods of energization of said magnet are disturbed.

2. In a secondary clock the combination with a train of means for retarding and means for accelerating its rate, an electro-magnet adapted to be energized for periods of definite extent by the master clock, a movable armature and means operated by its movement to retard the clock if it be too fast or to accelerate it if it be too slow, and thus bring it into synchronism with the master clock.

3. In a secondary clock the combination with a train of means for retarding and means for accelerating its rate, an electro-magnet adapted to be energized for definite periods of predetermined extent by a master clock, a movable armature and cam operated levers adapted to be shifted for definite periods by the clock mechanism and in fixed relation to the time as indicated by its hands, and to thereby cause said armature to actuate the retarding or the accelerating means and bring the clock into synchronism when the normal relations of said periods to those of the energization of the magnet are disturbed.

4. In a secondary clock the combination with a train of means for accelerating its rate, an electromagnet adapted to be energized for definite periods of predetermined extent by a master clock, a movable armature therefor, a cam operated lever adapted to be shifted by the clock for definite periods in fixed relation to the time as indicated by the clock, and to connect with said armature the accelerating means when the clock is too slow and the normal relation of its period of shift to the period of energization of the magnet is thereby disturbed.

5. In a secondary clock the combination

with the train of means for retarding its rate, an electromagnet adapted to be energized for definite periods of predetermined extent by a master clock, a movable armature therefor, a cam operated lever adapted to be shifted by the clock for definite periods in fixed relation to the time as indicated by the clock, and means controlled thereby for locking the armature against movement but

releasing the same and permitting it to actuate the retarding means when the clock is too fast and the normal relation of the period of shift of said lever to the period of energization of the magnet is disturbed. 10

In testimony whereof I hereunto affix my 15
signature.

JAMES W. BRYCE.
